[57] **CLAIM**

The ornamental design for a jug jacket, as shown and described.

DESCRIPTION

FIG. 1 is a top, left side, perspective view of a jug jacket of the present design;

FIG. 2 is a front elevational view thereof;

FIG. 3 is a top plan view thereof;

FIG. 4 is a rear elevational view thereof;

FIG. 5 is a left side elevational view thereof;

FIG. 6 is a right side elevational view

FIG. 7 is a bottom plan view thereof.
The broken line showing of the cap portion of the jug is for
illustrative purposes only and forms no part of the claimed
design.
